UNITED STATES PATENT OFFICE.

FREDERICK W. SUMNER, OF CANTON, MASSACHUSETTS, ASSIGNOR, BY MESNE ASSIGNMENTS, OF ONE-HALF TO FEDERAL MANUFACTURING COMPANY, OF HARTFORD, CONNECTICUT, A CORPORATION OF NEW JERSEY.

STOP-MOTION FOR WINDING-MACHINES.

No. 808,585.

Specification of Letters Patent.

Patented Dec. 26, 1905.

Application filed April 30, 1904. Serial No. 205,787.

To all whom it may concern:

Be it known that I, FREDERICK W. SUMNER, a citizen of the United States, residing at Canton, in the county of Norfolk and State of Massachusetts, have invented certain new and useful Improvements in Stop - Motions for Winding-Machines; and I do hereby declare the following to be a full, clear, and exact description of the invention, such as will 5 enable others skilled in the art to which it app pertains to make and use the same.

My invention relates to improvements in stop-motions; and the object of my invention is to provide a simple and easily-operated device of this class, and especially adapted for use in machines in which threads are wound 15 upon slivers forming cotton roving.

With this object in view my invention consists in the construction and combinations of 20 parts, as hereinafter described and claimed.

In the accompanying drawings, Figure 1 is a top plan view of my invention, and Fig. 2 is a cross-section thereof on the line 2 2 of Fig. 1 looking in the direction of the arrows.

25 *a* represents the roving, which is drawn from a suitable receptacle by means of parallel rollers, one of these rollers being lettered *b*, which are mounted in suitable bearings in frames *c c* and are driven by means of a belt passing over the pulley *d*, which is mounted 30 on the shaft of the roller *b*. *e* represents a loose pulley mounted on the same shaft. As the roving is drawn between the rollers, a plurality of threads, made of linen, cotton, or 35 other suitable material, are wound around said roving to strengthen it; and it is the object of my invention to provide means whereby if one of said threads should break the belt will be immediately and automatically 40 shifted from the fast pulley *d* to the loose pulley *e*. The threads *f* are carried upon spools *g*, which are pivotally mounted on brackets *h*, secured to one face of the pulley *i*. *j* represents a driving-belt for said pulley. This 45 pulley is mounted upon a hollow cylinder *k*, through which the roving passes. The cylinder is supported in suitable bearings *l*, mounted on the frames *m*.

On the exit of the cylinder *k* are mounted the 50 means serving to guide the threads from spools *g* around the roving *a* and for tripping the belt-shifter. These means consist, pref-

erably, of a collar or flange, in the periphery of which are formed slots *n*, one for each winding-thread, forming fixed guides through 55 which the threads are led and wound around the roving as the cylinder *k* revolves. Adjacent the slots *n* and preferably mounted on the face of the collar or flange are movable trippers *o*, preferably loosely pivoted in such 60 position that their ends project across the slots *n* and under the threads *f*, being thus held in position. The movable trippers *o* are preferably weighted, so that if one of them should be released by the breaking of a thread 65 it would quickly fly out by centrifugal force owing to the rotation of the cylinder *k* and automatically shift the belt, as hereinafter described. Pins (not shown) may be used, if desired, to prevent the guides *o* from falling 70 in toward the center of the cylinder *k*.

p represents a standard fixed to the floor or any suitable support, and on this standard is pivotally mounted a locking-arm *q*, one end of which is free and the other end of which 75 normally engages a notch in the upper part *r* of a slideable frame *s*, which slides in guides *t*, secured to the floor, or in any suitable way.

u represents projecting pins on the frame *s* forming a fork between which the belt 80 runs, so that the movement of the frame will shift the belt.

v represents a stout spring secured to one of the frames *m* and to the belt-shifting frame *s*, so that when the locking-arm *q* is 85 disengaged from the head *r* of the frame *s* the spring will bring the frame over until one of the pins *u* strikes one of the guides *t*, thereby shifting the belt from the fast pulley *d* to the loose pulley *e*. If a thread should break, one 90 of the movable trippers *o* would be thrown outward by centrifugal force and its end would strike the free end of locking-arm *q*, forcing it up and disengaging the other end from the head *r* of the frame *s*, whereupon 95 the belt would be immediately shifted. Instead of fast and loose pulleys any other form of shifting mechanism—as a friction-clutch, for example—may be used.

Having thus described my invention, what 100 I claim as new, and desire to secure by Letters Patent, is—

1. In a winding-machine, the combination with a driving-shaft actuated from a suitable

source of power, of means for winding the material under treatment with a strand of thread, fast and loose members on said driving-shaft, means for transferring the power from one member to the other, a locking-arm for said power-transferring means, and means operated by centrifugal force adapted to directly engage with and actuate said locking-arm when the thread breaks, substantially as described.

2. In a winding-machine, the combination with a driving-shaft actuated from a suitable source of power, of means for feeding the material under treatment, revolving means for winding a thread about said material, fast and loose members on said driving-shaft, means for transferring the power from one member to the other, a locking-arm for said power-transferring means, and means connected to rotate with said thread-winding means operated by centrifugal force and adapted to directly engage with and actuate said locking-arm when the thread breaks, substantially as described.

3. In a winding-machine, the combination with a driving-shaft actuated from a suitable source of power, of means for winding the material under treatment with a strand of thread, fast and loose members on said driving-shaft, means for transferring the power from one member to the other, a locking-arm for said power-transferring means, and a tripper operated by centrifugal force adapted to directly engage with and actuate said locking-arm when the thread breaks, substantially as described.

4. In a winding-machine, the combination with a driving-shaft actuated from a suitable source of power, of friction-rolls for feeding the material under treatment, revolving means for winding a thread about said material, fast and loose members on said driving-shaft, means for transferring the power from one member to the other, a locking-arm for said power-transferring means, and a tripper connected to rotate with said thread-winding means operated by centrifugal force and adapted to directly engage with and actuate said locking-arm when the thread breaks, substantially as described.

5. In a winding-machine, the combination with a driving-shaft actuated from a suitable source of power, of means for feeding the material under treatment, revolving means carrying spools of thread to be wound about said material, fast and loose members on said driving-shaft, means for transferring the power from one member to the other, a locking-arm for said power-transferring means, and a tripper for each spool connected to rotate with said thread-winding means operated by centrifugal force and adapted to directly engage with and actuate said locking-arm when any thread breaks, substantially as described.

6. In a winding-machine, the combination with a driving-shaft actuated from a suitable source of power, of a revolving cylinder provided at one end with means for supplying the material under treatment with a strand of thread and at the other with a guiding-slot for said thread, fast and loose members on said driving-shaft, means for transferring the power from one member to the other, a locking-arm for said power-transferring means, and a tripper held adjacent said slot by said thread and operated by centrifugal force to engage with and actuate said locking-arm when the thread breaks, substantially as described.

7. In a winding-machine, the combination with a driving-shaft actuated from a suitable source of power, of a revolving cylinder provided at one end with means for supplying the material under treatment with a strand of thread and at the other with a collar provided with a guiding-slot for said thread, fast and loose members on said driving-shaft, means for transferring the power from one member to the other, a locking-arm for said power-transferring means, and a tripper pivoted to said collar, held adjacent said slot by said thread and operated by centrifugal force to engage with and actuate said locking-arm when the thread breaks, substantially as described.

8. In a winding-machine, the combination with a driving-shaft provided with fast and loose pulleys and a belt-shifting device therefor, of means for winding the material under treatment with a strand of thread, a locking-arm for said belt-shifter, and a tripper operated by centrifugal force adapted to directly engage with and actuate said locking-arm when the thread breaks, substantially as described.

9. In a winding-machine, the combination with a driving-shaft actuated from a suitable source of power, of a revolving cylinder provided at one end with means for supplying the material under treatment with a strand of thread and at the other with a guiding-slot for said thread, fast and loose pulleys on said driving-shaft, a belt-shifting device, a locking-arm for said belt-shifter, and a tripper held adjacent said slot by said thread and operated by centrifugal force to engage with and actuate said locking-arm when the thread breaks, substantially as described.

10. In a winding-machine, the combination with a driving-shaft actuated from a suitable source of power, of a revolving cylinder provided at one end with means for supplying the material under treatment with a strand of thread and at the other with a guiding-slot for said thread, means for feeding the material under treatment therethrough, fast and loose pulleys on said driving-shaft, a belt shifting device, a locking-arm for said belt-shifter, and a tripper held adjacent said slot

by said thread and operated by centrifugal force to engage with and actuate said locking-arm when the thread breaks, substantially as described.

5 11. In a winding-machine, the combination of feeding-rolls, a fast and loose pulley mounted on the shaft of one of said rolls, a belt-shifting device for said pulleys comprising a spring, a sliding frame and a locking-arm for 10 said frame, a cylinder carrying spools of thread to be wound upon the material under treatment, and trippers carried by said cylinder adapted to swing outward by centrifugal force to engage with and actuate said locking-arm when a thread breaks, substantially as described.

15 12. In a winding-machine, the combination with feeding-rolls through which a sliver is fed and driving means therefor, of a cylinder 20 provided with guiding-slots in one end, mov-

able trippers adjacent thereto, means for rotating said cylinder and means mounted thereon for supplying said sliver with strands of thread, each thread being adapted to pass through one of said slots and over one tripper 25 respectively, and a belt - shifting device for said driving means consisting of a sliding frame provided with a fork, a spring connected to said frame, and a locking-arm adapted to normally engage said frame and constructed to be struck and actuated by one of said trippers when one of the threads breaks, substantially as described.

In testimony whereof I affix my signature in presence of two witnesses.

FRED. W. SUMNER.
